UNITED STATES PATENT OFFICE.

JOHN K. WHITTIER AND ROBERT S. CURLEY, OF LOWELL, MASSACHUSETTS, ASSIGNEES
TO SACO-Lowell SHOPS, OF LOWELL, MASSACHUSETTS, A CORPORATION OF MASSA-
CHUSETTS.

VERTICAL OPENER FOR CLEANING COTTON.

Application filed June 30, 1922. Serial No. 572,052.

To all whom it may concern:

Be it known that we, JOHN K. WHITTIER, a citizen of the United States, residing at Lowell, in the county of Middlesex and 5 Commonwealth of Massachusetts, and ROBERT S. CURLEY, a citizen of the United States, residing in said Lowell, have invented certain new and useful Improvements in Vertical Openers for Cleaning Cotton, of 10 which the following is a specification.

The object of our invention is to provide an improved grid for such an opener, that is durable, simple in construction, readily adjustable, and which permits ready and 15 easy access to the interior of the opener.

Vertical openers have long been in common use. We have shown our invention as applied to the well-known Crighton type of opener. In this type of opener, the cotton, 20 having been picked from the bale, is fed into the bottom of the machine, passed over a grid surface at high speed, and delivered from the top of the machine. In passing over the grid surface the stock is opened and 25 much of the sand, leaf, seeds and loose dirt is removed, and falls through the openings in the grid into the bottom of the machine.

Our invention consists in the construction, a preferred embodiment of which is shown in 30 the accompanying drawings.

In the drawings,

Figure 1 is a partial sectional view of the machine;

Fig. 2 is a vertical section (broken in two) 35 on the lines 2, 2, Fig. 4;

Fig. 3 is a top plan view of the lower half of Fig. 2; and

Fig. 4 is a top plan view of one-quarter section of the grid.

In the drawings, 1 is a cubical wall or housing with a cover 2. Near the bottom of the housing is the supporting frame or girt 3, which carries the thrust bearing 4 in which is revolvably mounted the vertical shaft 5, 40 which has a bearing at 6 and a belt pulley 7 by which the shaft can be revolved. At 8 is an inlet pipe through which the cotton is fed into the machine. The supporting frame 3 carries the casting 9 which forms the 45 base or support for the grid 10, and which has an opening 11 to which the inlet pipe 8 is attached. Bolted to a flange 12 of casting 9 is a circular plate 13, which, as shown in Fig. 3, has its outer circumference notched 50 as at 14. The top of the housing is formed

with a circular casting 15 on which the cover 2 is fitted and which with the cover forms the outlet chamber 16 with an opening 17 to which the outlet pipe 18 is attached. To the bottom face of casting 15 is fastened 60 the circular plate 19 which has slots 14' in which fit the tops of bars 23; hereinafter described. Plates 13 and 19 are preferably made in sections and are thereby more easily handled and cast. 65

The shaft 5 carries a series of discs 20 at varying heights within the grid 10, and to these discs are attached steel blades or fingers 21 which are bent to form a spiral from bottom to top. 70

At a suitable distance above the top of the grid, the shaft 5 carries a fan 22. The fan is revolved at high speed, creating a suction within the grid by which the cotton stock, assisted by the revolving blades 21, is 75 drawn in a spiral path from the inlet 11, across the surface of the grid in the direction of the arrow (Figs. 3 and 4) and delivered through the outlet 18.

Heretofore the grid in openers of the 80 character here shown and described has been formed in various ways. Sometimes the entire grid wall has been made of perforated metal. Another common form of grid has consisted of bars which are triangular in 85 cross-section and which are tapered, being larger at the top than at the bottom. It is desirable that the spaces or openings between the bars shall be substantially the same size, and that each opening shall be substantially uniform in cross-section from top to bottom. To obtain this result in a cone-shaped grid made up of bars, the bars must taper from top to bottom, since the top of the grid is of greater circumference than 90 the bottom. A perforated metal grid gives good results for certain classes of work, but under many conditions it is not entirely adequate. Moreover, it is not adjustable. A grid made up of tapered bars has certain 100 disadvantages. In order to provide for a sufficient number of openings between bars to do the work of the machine adequately, the bars can not be too large. If the bars are of a size to provide for an adequate 105 number of openings, the lower ends of the bars are quite small, with the result that they are so weak at the point where they are subject to the greatest strain from the pressure of the incoming cotton which has not been 110

completely opened, that they are apt to bend at their lower ends. Moreover, it is difficult to properly seat and hold fast such small lower ends and they are not readily capable of being moved or rotated by mechanical means in order to be adjusted.

We have found that a useful grid can be made by alternating sections of bars which are not tapered but uniform in size from top to bottom with metal sections or inserts. Referring to the drawings, the non-tapered grid bars are shown at 23 and are preferably triangular in cross-section, as shown in Fig. 3. The broadened or base portions of these triangular bars fit into the notches 14 and slots 14' in the plates 13 and 19. The first bar to be placed will be perpendicular and will form an element of the cone. But to make each opening between the bars substantially uniform in cross-section from top to bottom, the succeeding bars can not be placed so as to form elements of the cone, but they must diverge from such cone element position, the bars on one side of the first bar diverging progressively in one direction and the bars on the other side diverging progressively in an opposite direction. This progressive divergence of the bars must be compensated for, and preferably we compensate for it by the insertion of a number of triangular-shaped metal sections 24''. As shown in the drawings, we preferably use four such metal sections, each quarter section of the grid, therefore, consisting of a section of bars of uniform cross-section and the triangular metal insert. The number of metal inserts may be varied without departing from our invention. Also it is ordinarily desirable that the metal sections should be perforated so that they may contribute to the cleaning power of the grid.

While we have shown and described the bars as being substantially uniform in cross-section, grid bars might be made which are not uniform in cross-section throughout without departing from our invention, provided the working face of each bar is of substantially uniform width from top to bottom. By working face we mean that surface portion of the bar which faces the interior of the grid. Also, of course, the bars need not be triangular in cross section although such triangular bars are preferred.

It is desirable that the "rake" of grid bars of the general character here shown should be adjustable.

Experience has shown for instance that when triangular-shaped bars in a grid of this character are in the full line portion, (Fig. 3) a substantial amount of dirt and leaf will be detached from the fibres as they pass over the grid, and that when the bars are raked as shown in the dotted line

position (Fig. 3) there is an increased amount of dirt and leaf, more especially large unbroken leaf, removed from the fibres, and also a substantial number of very short fibres, unfit for spinning purposes, are detached from the mass of cotton and will fall with the dirt and leaf. The position of the bars depends upon the desires and requirements of the individual manufacturer, and upon the character and quality of the cotton which is being cleansed.

A preferred method of adjustment of the grid bars may be provided for by adjustment plates 24 and 24', preferably made in sections. Each section consists of a lower plate 24 which is bolted at 25 to the top outer edge of plate 13 and spaced therefrom by a boss 26. Plate 24 has two handles 27, 27', and a slot 28, in which the bolt 25 slides to permit the plate 24 to be moved with relation to plate 13. The inside edge of plate 24 has triangular notches 29 which engage the pointed edges of bars 23, as shown in Fig. 3. Similarly bolted to the under side of top plate 19 are plates 24' (Fig. 2) which have triangular notches 30, slots 31 and handles 32, the notches 30 engaging the pointed edges of bars 23 near the top thereof.

To adjust and alter the rake of the bars, fastenings 25 are loosened and plates 24 and 24' are moved, for instance, to the right (Fig. 3), which swings the bars 23 on points 33 as pivots to the dotted line position (Fig. 3).

We believe it desirable that different groups of bars should be capable of adjustment to varying degrees, independent of other groups. For this purpose, and also because it makes for accuracy of adjustment, we prefer to make the adjustment plates in reasonably small sections. We have shown in the drawings two such plates for each quarter section, both at the top and at the bottom.

Each metal section 24'' is made fast at its lower end by a screw 34, and each metal section has at its top projecting lugs 35 which fit into slots 36 in top plate 19. These triangular-shaped metal sections may be readily removed by simply removing the screw 34 and lifting the section until the bottom end can be swung out from beyond the bottom plate 13. This gives easy access to the interior of the grid without removing the bars or disturbing the adjustment thereof.

What we claim is:—

1. In a machine of the character described a conical grid having spaced grid bars all of which extend from top to bottom of the grid, the working face of each bar being substantially uniform in width throughout its length, each space between bars being substantially uniform in width

throughout its length, and means for compensating for the divergence of said bars from a cone element position.

2. In a machine of the character described 5 a conical grid made up in part of substantially triangular shaped plates or inserts and in part of spaced grid bars, the working face of each bar being substantially uniform in width throughout its length and extending 10 from top to bottom of the grid.

3. In a machine of the character described a conical grid made up in part of substantially triangular shaped plates or inserts and in part of spaced grid bars, the working 15 face of each bar being substantially uniform in width throughout its length and extending from top to bottom of the grid and each space between bars being substantially uniform in width throughout its length.

20 4. In a machine of the character described a conical grid made up in part of perforated plates or inserts and in part of spaced grid bars, each bar having a working face uniform in width throughout its length, each 25 space between bars being substantially uniform in width throughout its length, and means for varying the spaced distance between bars.

5. In a machine of the character described 30 a conical grid made up in part of plates or inserts and in part of spaced grid bars, the working face of each bar being substantially uniform in width throughout its length, each space between bars being substantially uniform 35 in width throughout its length, and means for varying the spaced distance between the bars of a group of bars independently of the other bars.

40 6. In a machine of the character described a grid made up in part of plates or inserts and in part of spaced bars, each bar having a working face substantially uniform in width throughout its length, top and bottom supporting plates, each plate having recesses, said bars being positioned at top and 45 bottom to turn in said recesses, adjustment plates adjustably attached to said supporting plates and engaging said bars, means for moving said adjustment plates and thereby turning the bars which they engage.

50 7. In a machine of the character described a conical grid made up of a plurality of triangular shaped perforated plates or inserts alternating with a plurality of series of spaced bars, each bar having a working face substantially uniform in width throughout its length and running from top to bottom of the grid, each space between bars being substantially uniform in width throughout 55 its length, and means for adjusting the rake 60

of said bars and the spaced distance between them.

8. In a machine of the character described a grid made up of a plurality of triangular shaped inserts alternating with a plurality 65 of series of spaced bars, the working face of each bar being substantially uniform in width throughout its length and running from top to bottom of the grid, and each space between bars being substantially uniform 70 in width throughout its length.

9. In a machine of the character described a grid made up of a plurality of triangular shaped inserts alternating with a plurality of series of spaced bars, each bar 75 being substantially triangular and uniform in cross-section throughout its length, and each space between bars being substantially uniform in width throughout its length.

10. In a machine of the character described a grid comprising top and bottom plates of different diameters, non-tapering bars engaged at top and bottom by said plates and spaced apart, triangular shaped metal sections positioned at intervals between said plates and between sections of said bars and having top lugs which engage in recesses in said top plate, adjustment plates adjustably fastened to said top and bottom plates and engaging said bars whereby said adjustment plates may be moved relative to said top and bottom plates and thereby move said bars as and for the purpose described.

11. In a machine of the character described an inverted cone-shaped grid comprising top and bottom circular plates of different diameters, each plate having notches in its outer circumference and the top plate having recesses therein, between said plates triangular shaped metal sections alternating with sections made up of non-tapering bars, said bars engaging in said notches and said metal sections having lugs which engage in said recesses, adjustment plates adjustably fastened to said top and bottom plates and having notches to engage said bars, means for moving said adjustment plates relative to said top and bottom plates thereby altering the position of the bars which they engage, as and for the purpose described.

In witness whereof, we have signed our names to the foregoing specification in the presence of two witnesses.

JOHN K. WHITTIER.
